UNITED STATES PATENT OFFICE.

LORENZO T. HAMMOND, OF COTUIT, MASSACHUSETTS.

DIE-STOCK.

1,209,960.

Specification of Letters Patent. Patented Dec. 26, 1916.

Application filed March 29, 1916. Serial No. 87,876.

To all whom it may concern:

Be it known that I, LORENZO T. HAMMOND, a citizen of the United States of America, and a resident of Cotuit, in the county of Barnstable and State of Massachusetts, have invented certain new and useful Improvements in Die-Stocks, of which the following is a specification.

This invention relates to die stocks and particularly to devices of this character that are adapted for cutting tapered threads in pipes and has for its object the provision of means adjacent to the cutting tools for centering pipes of various sizes whereby a more perfect cutting operation is assured.

Where die stocks are used with guide members located at some distance from the cutting tools the end of the pipe is liable to be moved sidewise during the thread cutting operation, and a very imperfect cutting of the thread results, said thread being shallow at some points and quite deep at other points. This difficulty is overcome by providing in addition to the usual pipe supports other centering devices adjacent to the cutting tools, which centering devices effectually prevent any play of the pipe while the thread is being cut thereon.

The invention consists primarily in providing the die stock housing with centering devices adjustably mounted therein adjacent to the thread cutting tools and in the path of movement of said cutting tools.

The invention further consists in certain novel features of construction and arrangement of parts which will be fully understood by reference to the description of the drawings and to the claims hereinafter given.

Of the drawings, Figure 1 represents a plan of a die stock embodying the principles of the present invention. Fig. 2 represents a front elevation of the same. Fig. 3 represents a transverse vertical section of same on line 3—3 on Fig. 1. Fig. 4 represents a transverse vertical section of same on line 4—4 on Fig. 1. Fig. 5 represents a longitudinal vertical section of the same on line 5—5 on Fig. 1. Fig. 6 represents a transverse vertical section of the same on line 6—6 on Fig. 1, and Fig. 7 represents a transverse vertical section of the same on line 7—7 on Fig. 1.

Similar characters designate like parts throughout the several figures of the drawings.

In the drawings, 10 is an annular frame having a forward projection 11 at the front end of which is formed a nut 12 adapted to receive the threaded tubular hub 13 of a die stock housing 14. The frame 10 is provided with a plurality of radial slots 15 in each of which is mounted a member 16 adapted to be moved longitudinally therein. Each member 16 is provided with a transverse slot 17 in one face into which extends a curved rib 18 formed upon an annular plate 19 surrounding the hub of the annular frame 10 and held in position by means of a nut 29 threaded to the extreme end of said hub, as indicated in Fig. 5 of the drawings. Each curved rib 18 is eccentric to the axis of said frame 10, as indicated in Fig. 7 of the drawings. The ring 19 is provided with an outwardly extending projection 21, by which the ring 19 may be moved about the axis of the frame 10 to move the members 16 inwardly and outwardly as desired so that their inner ends will contact with any size of pipe on which it is desired to cut threads.

When a pipe has been positioned within the frame 10 and the members 16 have been forced into contact therewith by the movement of the annular plate 19 about its axis, the frame 10 is prevented from rotating about the pipe thus centered by means of the locking member 22 threaded to one of the members 16.

The outer end of the member 22 has pivoted thereto a handle 23 by which said threaded member 22 may be rotated about its axis and jammed against the periphery of the pipe being operated upon. Surrounding the forwardly extending portion 11 of the frame 10 is a ring 24 having a plurality of transverse depressions 25 in a portion of its periphery. Surrounding the ring 24 is an annular operating member 26 retained in position between the flanged end of the ring 24 and its opposite end by means of a plate 27 secured to said ring 24. This operating member 26 is provided with oppositely disposed hubs 28 adapted to receive the handles 29 by which the operating member 26 may be moved about the axis of the frame 10 in either direction. The operating member 26 has mounted therein a radial dog 30 the inner end of which is adapted to enter and coact with the depressions 25 in the ring 24. This dog is forced inwardly by means of a spring 31 surrounding the reduced shank 32

of said dog, said shank having a milled end 33 by which the dog 30 may be rotated in its bearing when it is desired to change the direction of movement of the ring 24. The tension of the spring 31 is regulated by means of the adjustable member 34. When the dog is in the position indicated in Fig. 3 of the drawings, any movement of the operating member 26 in the direction of the arrow *a* on said figure will cause the ring 24 to be moved about the axis of the frame 10 in the direction of the arrow *b* on said figure. When the operating member 26 is moved in the direction opposite to that indicated by the arrow *a*, the ring 24 will remain at a standstill and the dog 30 will be moved outwardly against the tension of the spring 31 until it engages with the wall of another depression 25, after which a further movement of the operating member 26 in the direction of the arrow *a* will transmit to the ring 24 a further movement of said ring in the direction of the arrow *b*. When the dog 30 has been rotated 180° in its bearing, movement will be imparted to the ring 24 by the operating member 26 in a similar manner but in a direction opposite to that indicated by the arrow *b* on Fig. 3 of the drawings.

30 The ring 24 is provided with two arms 35 extending through openings 36 in ears 37 formed upon the housing 14. It is obvious, therefore, that when the ring 24 is rotated in either direction, the housing 14 will be simultaneously rotated in the same direction. In view of the fact that the nut 12 upon the frame 10 is held stationary during the rotation of the ring 24 and the housing 14, the rotation of the threaded hub 13 of the housing will cause said housing to be moved toward or from the ring 24 according to the direction in which said ring is being rotated.

The housing 14 is provided with a plurality of radial grooves 38 in each of which is mounted a cutting tool or chaser 39. Each cutting tool 39 is provided with a lateral lug 40 extending into a curved groove 41 formed in an annular plate 42 surrounding the forward hub 43 of the housing 14. The curved grooves 41 are formed in the plate 42 eccentrically to the axis of the housing 14, as clearly shown in Fig. 6 of the drawings. Bearing against the outer face 55 of the annular plate 42 is another annular plate 44 surrounding a hub 43 and having a projecting lug 45 extending therefrom into an inclined slot 46 in one of the arms 35 projecting forwardly from the ring 34. The plates 42 and 44 are held in position upon the hub 43 by means of an annular plate 47 secured to the hub 43 by means of the screws 48.

65 The plate 42 is provided with a radial ear 49 on which is mounted a laterally threaded

stud 50 and a steady pin 51. Mounted upon the stud 50 and pin 51 is a clamping plate 52, the end of which overlaps the plate 44 and is adapted to be forced into gripping contact therewith by means of the nut 53 threaded to the stud 50. When the plate 52 is forced into gripping contact with the plate 44, the two plates 42 and 44 will rotate together.

The device as heretofore described is a well-known construction of die stock for cutting tapered threads in pipes. The difficulty that has been found to exist in this form of pipe cutting device is that in the cutting operation the chasers or cutting tools 39 will force the unsupported ends of the pipe laterally, and thereby cause a very imperfect cutting operation, the threads at some points being very shallow and at other points quite deep. Very often, owing to the imperfect cutting of the threads, it is necessary to cut new threads, and sometimes an entire job is spoiled by the imperfect operation of the thread cutting device. If the pipe is used with the imperfect thread cut thereon, it is difficult to keep the joint in the assembled pipes tight. The imperfect cutting of the threads occurs more often in brass pipe than in iron pipe, but occurs to a greater or less extent even in the latter. It is self-evident that it is desirable to overcome these objections, and this is accomplished by providing the housing 14 with a plurality of pipe centering devices 54 which extend radially into the interior of said housing. These centering members 54 are adjacent to the chasers or cutting tools 39 and between them and the supporting members 16. It is obvious that when the centering devices 54 are provided in addition to the supporting members 16, and the former are located in close proximity to the cutting members or chasers 39, there can be no lateral movement of the unsupported end of the pipe.

During the rotation of the housing 14 the inner ends of the members 54 will travel over the periphery of the pipe immediately in advance of the cutting tools 39, and as a consequence of this contact between the inner ends of said centering devices 54 of the periphery of the pipe, the same depth of teeth will be insured throughout the cutting operation.

The members 54 extend through radial openings 55 in the housing 14, and each is provided with a lug or projection 57 extending into eccentric grooves 58 formed in the annular plate 59 set into a recess 60 in the rear face of the housing 14. The plate 59 is provided with a handle 61 by which the said plate may be rotated in either direction about the axis of the housing 14. Displacement of the plate 59 from the recess 60 may be prevented in any well-known manner such as by means of the clips 62 secured to the

housing 14 and extending over the outer face of said plate.

Secured to the rear face of the housing 14 is a threaded stud 63 on which is mounted a 5 clamping nut 64 adapted to bear against the face of the plate 59 and lock it in its adjusted position. When the cutting device has been placed upon a pipe into the periphery of which it is desired to cut a thread, the 10 supporting members 16 are adjusted so that their inner ends bear firmly upon one portion of the pipe and the locking member 22 is then adjusted so that the rotation on the pipe of the frame 10 is prevented. The 15 centering members 54 are then moved into contact with the periphery of the pipe at its extreme outer end and then the plate 59 is locked in its adjusted position by means of the clamping member 64. The chasers 39 20 are adjusted for the proper size of pipe and are locked in their adjusted positions by means of the clamping devices 52—53. When these adjustments have been made the operation 25 of cutting the threads in the pipe is effected in the same manner that the threads would be cut by the device before the present improvements had been applied thereto.

It is believed that the operation and many 30 advantages of this invention will be fully understood from the foregoing description.

Having thus described my invention, I claim:

1. In a device of the class described, the 35 combination of a housing; a plurality of radial cutting tools therein; means for adjusting said tools for different sizes of pipes; a plurality of radial pipe centering devices mounted in said housing adjacent to said cutting tools; means for adjusting said centering devices for various sizes of pipes; 40 means for rotating said housing; and means

for continuously moving said cutting tools outwardly during the rotation of said housing.

2. In a device of the class described, the 45 combination of an annular frame; means for centering a pipe therein; means for clamping said frame to said pipe; a nut secured to said frame; a housing provided with a tubular portion threaded to said nut; means for 50 rotating said housing; a plurality of radial cutting tools mounted in said housing; a plurality of radial centering devices also mounted in said housing between said cutting tools and said threaded tubular portion; 55 independent means for adjusting the positions of said cutting tools and centering devices; and a locking device for each adjusting means.

3. In a device of the class described, the 60 combination of an annular frame; means for centering a pipe therein; means for clamping said frame to said pipe; a nut secured to said frame; a housing provided with a tubular portion threaded to said nut; means for 65 rotating said housing; a plurality of radial cutting tools mounted in said housing; a plurality of radial centering devices also mounted in said housing between said cutting tools and said threaded tubular portion; 70 independent means for adjusting the positions of said cutting tools and centering devices; a locking device for each adjusting means; and means for constantly moving 75 said cutting tools outwardly during the rotation of said housing.

Signed by me at 4 Post Office Sq., Boston, Mass., this 28th day of March, 1916.

LORENZO T. HAMMOND.
